UNITED STATES PATENT OFFICE.

BRUCE A. BRISTOW, OF TORONTO, ONTARIO, CANADA.

HYDRAULIC POWER DEVICE.

Application filed December 1, 1923. Serial No. 678,047.

To all whom it may concern:

Be it known that I, BRUCE A. BRISTOW, of the city of Toronto, in the county of York, Province of Ontario, Canada, a subject of the King of Great Britain, have invented certain new and useful Improvements in Hydraulic Power Devices, of which the following is a specification.

This invention relates particularly to means for advantageously using water power where the head is low and the flow relatively large but which may be used with any available head and comprises in essence a crib or chamber having gate controlled openings in its bottom vertically movable in a stationary chamber communicating at its upper part with the water reservoir and having a gate controlled outlet at the lowest practical level. Means are provided whereby the outlet gate of the stationary chamber may be opened when the crib is in its uppermost position thus allowing the water in said chamber to escape and the crib to descend. Means are also provided for opening the gates in the bottom of the crib when it has reached its lowermost position so that, the outlet gate of the stationary chamber having been previously closed, the crib may be readily raised to its initial position. Means are provided for equalizing the pressure above and below the bottom of the crib, when it is in its lowermost position, to facilitate the opening of the gates therein and means are also provided to convert the reciprocating rectilinear movement of the crib into rotary movement convenient for power transmission.

The invention is hereinafter more specifically described and is illustrated in the accompanying drawings in which

Fig. 1 is a vertical section of the apparatus;

Fig. 2 a plan view of the same;

Fig. 3 a vertical section of the lower part of the apparatus with the crib in its lowermost position; and

Fig. 4 an enlarged cross section of the bottom of the crib.

In the drawings like numerals of reference indicate corresponding parts in the different figures.

1 is a water reservoir, which may be either natural or artificial, and which is enclosed by the retaining walls 2. In one of these

walls is formed an opening 3, which preferably should be of such depth that the reservoir may be drained so that water power is available as long as any water is contained in the reservoir. This opening communicates with the upper part of a stationary chamber 4, the lower part of which extends downward as far as the available fall permits. This chamber, adjacent its lower end, is provided with the outlet 5 controlled by the gate 6, which is shown as vertically slideable in suitable guides. The bottom of the chamber is below the level of the under side of the outlet opening 5, thus forming a well whose function will hereinafter appear.

Vertically movable in this chamber is a hollow crib or chamber 7, which has an opening in its side adjacent the opening 3, of sufficient height to maintain communication with said opening whether the crib be in its uppermost or lowermost position. When the crib is in its uppermost position, the bottom will be at or below the lower edge of the opening 3, while in its lowermost position its bottom will lie within the well at the bottom of the stationary chamber 4.

The walls of the crib are of such a height that they will be above the maximum water level in the reservoir at all times. In the bottom of the crib are formed one or more openings controlled by hinged gates 8 operated as hereinbefore described.

The crib is suitably guided within the stationary chamber, as, for instance, by the anti-friction rollers 9 on the crib running on the guides 10 on the stationary chamber. The escape of water from the reservoir round the sides of the crib is prevented by suitable packing strips 11 on the crib working in grooves 12 in the end walls of the stationary chamber.

Power is derived on the down stroke from the vertical movements of the crib, which movements are determined by the opening and closing of the gates 6 and 8. Assuming the crib to be in its uppermost position as shown in Fig. 1, the outlet gate 6 is opened. The water in the stationary chamber below the crib is thus allowed to escape, whereupon the weight of water in the crib causes the latter to descend. As soon as the water in the lower part of the stationary chamber has escaped, the gate 6 is closed while the crib continues to descend, any air in the chamber

being displaced upwardly between the walls of the crib and the chamber.

When the bottom of the crib descends into the well at the bottom of the chamber, part 5 of the water therein is displaced upwardly round the sides of the crib. As soon as the water in these spaces reaches the level of the water in the reservoir the pressure above and below the bottom of the crib is balanced. 10 There is then no pressure on the gates 8, which are easily opened or if lighter than water will open automatically. The crib is then free to rise, as the water above it readily passes through the bottom into the stationary chamber as fast as the crib rises. 15

The crib may be of wood, or may be otherwise made sufficiently buoyant to float upwardly and its upward movement is preferably assisted by a counterbalancing weight. 20 This is preferably arranged in connection with the means for converting the rectilinear movement of the crib into a rotary movement. For this purpose I provide a shaft 13, which is suitably journaled and will 25 usually be of sufficient length to serve several power units, as in order to secure a continuous output of power, I prefer to employ two or more units such as described side by side. This shaft carries a drum 14 on which 30 is wound the cable 15 connected by suitable bridles 16 to the crib. This drum has a pawl and ratchet connection 17 with the shaft. The end of the cable 15 has the counterbalancing weight 18 secured thereto. It follows therefore that as the crib rises either by flotation or by the operation of the weight 35 18 or by both combined, that the drum revolves freely on the shaft, while when the crib descends, the pawl and ratchet engage 40 and the shaft is rotated. This shaft may be used to operate electric generators for generation and transmission of electrical energy.

To synchronize the operation of the gates 45 8 any suitable mechanism may be employed. I show for this purpose a pair of crank disks 19 journaled at the bottom of the crib. A connecting rod 20 is journaled on wrist pins on these crank disks and this in turn has pivotal connections with the hinged gates 8. By imparting a partial movement of rotation to the disks 19, the gates may be closed or opened. I prefer, however, that the gates should be so constructed as to be lighter than water in which case the main function of the constructions just described is to synchronize the movements of the gates 8.

It is preferred, however, to employ in connection with one or more of the disks 19 a helical spring 21 connected to the disk and its axle which tends to hold the gates upright, when open, but which is powerless to open them when they are closed and the 60 65 water pressure is on them.

The gates are preferably closed by contact of one or more of the gates with a stationary stop 33 at the top of the stationary chamber.

To operate the gate 6 I provide an electric motor 24 which is geared to a drum 25 on which is wound a cable 26, the other end of which is connected with the gate. The weight of the gate will usually be sufficient to ensure its closing by gravity. The cable 26 is kept taut and the gate to which it is connected partly counterbalanced respectively by the weight 28 connected with its free end. The control of the motor for opening and closing the gate 6 may be effected manually, though it will be preferable to provide automatic means therefor. For this purpose I provide the circuit 22 of the motor 24 with two switches 29 and 30. The first switch is closed by the projection 31 on the crib as the latter reaches a point very slightly below its uppermost position and the motor thus started. The other is opened by a projection 32 on the gate when the latter has been sufficiently opened and the motor is thus stopped to permit the gate to close. 90

The movement of the gate 6 in opening and closing not being very rapid, the water in the lower part of the chamber 4 has ample time to escape.

While I do not desire to restrict myself I deem it important that the range of vertical movement of the crib be less than the available fall. For instance I consider that a range of movement of about five feet is best no matter what the available head may be. 95

What I claim is:

1. A hydraulic power device comprising a reservoir; a stationary chamber having the upper part of one side open to the reservoir and extending downwardly to provide a suitable fall; a crib vertically movable in said chamber and having an opening in one side adapted to maintain communication with the opening in the side of the stationary chamber as the crib rises and falls; a gate controlled outlet adjacent the bottom of the chamber; and a gate controlled outlet in the bottom of the crib. 105

2. A hydraulic power device comprising a reservoir; a stationary chamber having the upper part of one side open to the reservoir and extending downwardly to provide a suitable fall; a crib vertically movable in said chamber and having an opening in one side adapted to maintain communication with the opening in the side of the stationary chamber as the crib rises and falls; a gate controlled outlet above the bottom of the chamber, the bottom of the chamber thus forming a well which the bottom of the crib 115 may enter to displace water therein; and a gate controlled outlet in the bottom of the crib. 120

3. A hydraulic power device comprising a reservoir; a stationary chamber having the 130

upper part of one side open to the reservoir and extending downwardly to provide a suitable fall; a crib vertically movable in said chamber and having an opening in one side adapted to maintain communication with the opening in the side of the stationary chamber as the crib rises and falls; a gate controlled outlet adjacent the bottom of the chamber; a plurality of gate controlled

outlets in the bottom of the crib; and operating means connected with said gates whereby they may be simultaneously closed.

Signed at Toronto, Canada, this fifth day of November 1923.
